(57) **CLAIM**

The ornamental design for a shoe sole, as shown and described.

DESCRIPTION

FIG. 1 is a lateral side view of a shoe sole;

FIG. 2 is a first perspective view of the shoe sole;

FIG. 3 is a second perspective view of the shoe sole;

FIG. 4 is a lateral side view of a first element of the shoe sole;

FIG. 5 is a first perspective view of the first element of the shoe sole;

FIG. 6 is a second perspective view of the first element of the shoe sole;

FIG. 7 is a top view of a second element of the shoe sole;

FIG. 8 is a lateral side view of the second element of the shoe sole;

FIG. 9 is a first perspective view of the second element of the shoe sole; and,

FIG. 10 is a second perspective view of the second element of the shoe sole.

The broken lines depict environmental structure that is included for illustrative purposes only and forms no part of the claimed design.

1 Claim, 5 Drawing Sheets
